CHARLES J. GUENTHER, OF BOSTON, MASSACHUSETTS, ASSIGNOR TO STICKLE STEAM SPECIALTIES COMPANY, OF INDIANAPOLIS, INDIANA, A CORPORATION.

RECORDING DEVICE FOR PAPER MACHINES.

Application filed November 2, 1925. Serial No. 66,300.

This invention is a device for the permanent and continuous recording, in a paper machine, of the condition of the paper relative to moisture and dryness, and the amount 5 of live steam and exhaust steam being employed to heat the rolls and paper and various changes and emergencies arising in the operation of the paper machine.

The chief feature of the invention consists 10 in the combination with the mechanism in the paper machine, a recording device adapted for making a permanent record of said operations of the machine. In this it is particularly adapted for use in paper machines 15 wherein the supply of heat and moisture through the rolls and sheet of paper is controlled by the sheet of paper, by its tautness due to a relative dry condition, and its slack, due to a relative moist condition. To that 20 end the sheet of paper controls an auxiliary valve which controls fluid under pressure, such as city water supply, which operates and controls the valve mechanisms for controlling the live steam and also the exhaust 25 steam, and mounting in connection with such control a recording device so as to be operated thereby, as hereinafter more fully set forth.

The full nature of the invention will be 30 understood from the accompanying drawings and the following description and claims:

In the drawings, Figure 1 is a side elevation of a portion of the paper making machine, parts being in section and parts being broken away. Fig. 2 is a front elevation of the valve control means for controlling the supply of live and exhaust steam to the machine, with the recording device attached thereto. Fig. 3 is a rear elevation of the recording device and a section of said valve control means. Fig. 4 is a central vertical section on the line 4—4 of Fig. 3, through the recording device. Fig. 5 is a modified 45 form similar to Fig. 3. Fig. 6 is a perspective view of the rock shaft construction with the shaft which operates the pilot valve.

There is shown herein a paper making machine having a frame 10 mounted upon a floor 11 and carrying hollow drying cylinders 12 over which a sheet of paper 13 passes through the machine. The sheet of paper is dried by heat being introduced into the cylinders through pipes 14 extending up 55 from a steam header 15 to the cylinders. It

is preferable to use as much exhaust steam as possible in drying paper because it is economical and, therefore, an exhaust pipe 16 leads from the engine, not shown, to the header 15, but the exhaust steam supply cannot wholly be relied upon and, therefore, live steam is introduced into the header 15 through a live steam pipe 17 leading from a riser 18 which leads from a horizontal live steam pipe 19 coming from the other side of 60 the machine, as shown in Fig. 1. There is a return header 20 connected with the cylinders by pipes 21 and with a vacuum pump, not shown, for returning the air and water from the drying cylinders. 65

The supply of exhaust steam is controlled by a valve mechanism 22 and the live steam supply is controlled by a valve 23 in a by-pass pipe 24 forming a shunt connection between the riser 18 and the pipe 17. There 70 is a shut-off valve 25 in the pipe 17 and a similar valve 26 in the riser 18 and a similar valve 27 in the by-pass 24, whereby the live steam coming through the supply pipe 19 may be prevented from directly entering the 75 pipe 17 by closing the valve 25 and then letting it pass around through the by-pass 24. Also the steam can be wholly directed, if desired, through the pipe 17 by opening the valve 25 and closing the pipe 26. The 80 valve 27, which is operated by hand, enables the capacity of the by-pass 24 to be set or regulated. 85

The valve 22 and the live steam valve 23 are regulated and actuated by connections 90 with a vertically-moving water piston rod 30 operated in a vertical cylinder 31 secured to a vertical plate 32 rigidly mounted. The upper end of the water piston rod 30 is actuated by a cross head 33 operating on vertical 95 guide rods 34, and said piston rod carries at its upper end a cross rod 35, as shown in Fig. 2. To one end of said cross rod a chain 36 extends down to a valve lever 37 that is fulcrumed at 38 in a frame 39. As the piston travels upward, it will tend to close the exhaust valve 22 and as it travels downward, the weight of the lever 37 will tend to open 100 said exhaust valve. 105

The live steam valve is operated by a lever 40 fulcrumed at 41 on a frame 42, and carrying a weight 43. Gravity acting on the lever and weight tend to open the live steam valve 23, and its closing movement is caused by a chain 44 secured to the outer end of the lever 110

40 and passing through a sheave wheel 45 on the cross bar 35 operating the piston rod, and the other end of said chain 44 extends down and is secured to an arm 46 which is 5 adjustably fastened on the cylinder pipe 31.

The piston rod 30 in the cylinder 31 is actuated and controlled by fluid under pressure, usually water from a city water system that comes in through a city water pipe 10 50 and up through a riser pipe 51 and a pipe 52 leads from the pipe 51 to the lower end of the cylinder 31, and there is a shut-off valve 53 in the pipe 51 to the right hand or beyond the pipe 52. The water pressure in the

15 pipe 51 is controlled by a pilot valve 55 which has an upwardly-extending valve stem 56 operating in a frame 57 secured to the frame of the machine near the end of the cylinder over which the sheet of paper 13

20 passes. Said valve is operated and controlled by an arm 58 secured to a shaft 59 that extends entirely across the machine and has secured on each end an arm 60 that is pivotally connected by a 25 vertical rod 61 pivoted to a vertical arm 62 which is secured to a rock shaft 63 mounted on a frame 64 and extending across the machine, substantially as indicated in Fig. 6. The shaft 50 at each end has secured on

30 it an arm 65 extending downwardly at an inclination, as shown in Fig. 1, and each arm carries on its end a roll 66 adapted to engage the sheet of paper 13. The lever 58 is counterbalanced by a weighted arm 67.

35 The mechanism just described provides for automatic steam control by the tension of the sheet of paper through an auxiliary pilot valve. The means for controlling the supply of steam to the paper drying cylinders is sub-

40 stantly of the same nature as that set forth in the patent granted to Cole Stickle, on October 9, 1917, No. 1,242,387, for heat control for paper making machines, and the operation of the mechanism heretofore de-

45 scribed is as follows: When the sheet of paper 13 draws up slightly by drying, it opens the auxiliary pilot valve 55 which admits the auxiliary city water pressure through pipes 51 and 52 to the bottom of the 50 cylinder 31, which forces the piston rod 30 upward. The upward movement of the piston closes the live steam valve 23 by the

chain 44 connected to the lever 40 or weight 43, if desired. When the sheet of paper be-

55 comes slack by reason of moisture, the oppo- site action will take place so that the live steam valve would be open, should the ma- chine require a constant make-up of live steam. The auxiliary or pilot valve 55

60 would move to open and closed positions with the change of the moisture condition of the sheet of paper, whereby it is rendered more taut by drying or slack by moisture, and thus said auxiliary or pilot valve would 65 automatically admit live steam and shut it

off, as the drying sheet requires. The ex- haust steam valve is set so that it does not close when the live steam valve closes, but should the exhaust steam suffice to dry the sheet of paper, as the sheet becomes dry and 70 more taut, the piston rod 30 would travel up and close the live steam valve. Should the sheet require less exhaust steam, the piston rod 30 will continue to travel upward and will partially close the exhaust valve 22 and 75 would travel up or down as the condition of the paper causes it to travel and thus admit more or less steam as might be required to dry the sheet.

When the auxiliary or pilot valve 55 80 closes, the auxiliary pressure leaks away, allowing the piston rod 30 to move down- ward. When the auxiliary or pilot valve 55 opens again, it builds up the pressure be- 85 neath the piston in the cylinder 31 and the piston rod travels upward again. This en- ables a sheet of paper to be dried evenly by 90 automatic control that varies the steam in the cylinders according to the slight varia- tion that comes from free to hard drying 95 stock. The back tender never knows when this change is coming and consequently the sheet of paper gets either too dry or too damp unless the machine be equipped with an automatic heat control. With this steam 100 control one can get an evenly dried sheet of paper because the control is mechanical and automatic.

A permanent record of the tension of the sheet of paper as it goes through the ma- 100 chine, and, therefore, its condition from time to time, is made by combining with the fore- going mechanism, which will hereafter be ex- plained. This recorder also shows to what extent live steam is employed and exhaust 105 steam for drying the sheet of paper, from time to time, during the operation of the machine for twenty-four hours, and by that record the operator of the machine is enabled to adjust the machine so it will operate 110 more satisfactorily and smoothly and use as little live steam as possible and depend as much as possible upon the exhaust steam. The record will also show any accidental or 115 emergency conditions of the sheet of paper or operation of the machine, as will be ex- plained.

On the cylinder tube 31, as shown in Fig. 2, a cylindrical casing 70 is secured by clamps 71, so that the same will be visible. 120 The casing, as shown in Fig. 4, has a glass front 72, and in said casing there is secured a clock 73 by a clamping ring 74 secured to the frame arm 75, as seen in Fig. 3. The details of this clock are not shown, but it 125 is a spring clock of usual type and has a shaft 76 extending centrally through it which is operated by the clock mechanism and which carries on one end a rotating dial chart 77, as seen in Fig. 2. This chart lies 130

immediately behind the glass front 72 and it rotates slowly, making one revolution in twenty-four hours, and it has the hours from noon to midnight and from midnight to noon marked on the margin thereof, and it also has what may be termed a normal line 80 marked thereon.

A pen holder 81 extends up in front of the chart and to one side of the center substantially as shown in Fig. 6, so that the upper end would normally register with said normal line 80 and in its upper end it carries a pen 82. The pen holder 81 is at its lower end secured to a shaft 83 mounted in a bearing sleeve 84 on an arm 85 extending downward from the clamping ring 74 that holds the clock. As the ring is oscillated, it travels and marks on the chart lines almost radial in direction, across the normal line 80.

The recording pen is actuated and controlled by the following means: A cord or chain 86 is secured at its upper end to the cross rod 35 and at its lower end said cord 25 extends several times around a pulley 87 on a shaft 88 mounted concentrically of the clock and in alignment with the clock shaft 76, but independently thereof. The outer end of the shaft 88 is mounted in a bearing 30 89 and has secured on its outer end a pinion 90 that meshes with a spur gear 91 below it which is mounted in a frame arm 92 and eccentrically pivoted to the spur gear 91 there is a link 93, as seen in Fig. 3, that extends to a long arm 94 which is secured to the shaft 83, shown by dotted lines in Fig. 4, that operates in the bearing 84. When the piston rod goes up, therefore, the pulley 87 will be turned counterclockwise for moving the pen 82 in one direction and when the piston rod goes down, a spring 110 associated with the frame of the clock and the pulley 87 returns said pulley and gives it a clockwise movement which enables the cord 86 40 to be taut and moves the pen 82 in the opposite direction.

A modified means is shown in Fig. 5 for operating the pen, the only change being that instead of the pinion 90 there is a worm 50 pinion 100 that meshes with the worm wheel 101 which are mounted on an arm 102 from the frame member 74 and the connecting bar 93 is eccentrically pivoted to the worm gear 101 by a connection 103.

The operation of the recording device is as follows: As the sheet of paper 13 becomes drier and more taut, and the piston rod 30 moves upward as heretofore explained, it will turn the pulley 87 counterclockwise and, therefore, move the pen radially of the chart towards the center of the chart and when the sheet is relatively moist and slack, the piston rod 30 will move downward correspondingly and the pen will be caused to move across the dial in the opposite direc-

tion, that is, away from the center of the chart. Hence, as the machine operates, the pen will oscillate more or less in one direction and near the normal line 80 as the dial is slowly rotated by the clock. The parts 70 of the mechanism are preferably set when the machine is operated at its best, so that the pen will register substantially with the normal line 80. The pin, therefore, records the tension of the paper. When the tension 75 increases beyond normal, the lines extend inward, and when the tension diminishes and the slack increases beyond normal, the recording lines extend outward beyond the normal line 80 so that the chart gives a 80 twenty-four hour record of the condition of the paper and its tension and its dry and moist conditions from time to time.

The recording device also indicates the steam supply for heating the cylinders. 85 The recording lines 105 that extend outward from the normal line 80, indicate that live steam is used in addition to exhaust steam, and the further out the lines extend, the more live steam is being used which is an 90 undesirable condition from the standpoint of economy. The recording lines 105 extending inward from the normal line 80 indicate that exhaust steam only is being used to dry the paper and the further inward the 95 lines extend, the less exhaust steam is being used. The idle condition of the paper and of the steam control is indicated by slight variation of the pen marks from the normal line 80, preferably on the inside of said line. 100 When, however, there is a wash up, a wide sweeping movement of the recording pen produces long transverse lines, as at 106, and the same result happens when they are bringing the paper over or if the sheet of 105 paper should break.

Hence, this recording device not only records the condition, tension and dryness or moistness of the sheet of paper, but it also indicates when live steam is being used 110 and to what degree and also to what extent exhaust steam is being used; and it also indicates, as stated above, when the sheet of paper breaks or there is a wash up or paper is being brought over the cylinder, or any 115 emergency or accidental condition.

The invention claimed is:

1. In a paper making machine having means controlled by the tautness of the sheet of paper for controlling the heat in drying 120 the same as it passes through the machine, and a recording device, a connection between said heat controlling means and recording device for operating the recording device whereby it will record and indicate the tautness of the sheet of paper during its manufacture.

2. In a paper making machine having means controlled by the tautness of the sheet of paper for controlling the heat for 130

drying the same as it passes through the machine and a clock-operated recording device having a time chart and a pen for making the same, a flexible connection attached 5 at one end and movable by said heat controlling means and the other end thereof operatively connected with said pen for operating the same.

3. Apparatus substantially as set forth in 10 claim 2, said connection between the heat

controlling means and the recording device consisting of a pulley secured on the recording device, a flexible connection from said heat controlling means to said pulley for turning it in one direction, a spring for re- 15 turning the pulley, and means operated by said pulley for operating the pen.

In witness whereof, I have hereunto affixed my signature.

CHARLES J. GUENTHER.
